UNITED STATES PATENT OFFICE

136,601

DESIGN FOR A LATHE

William F. Groene, Cincinnati, Ohio, assignor to
The R. K. Le Blond Machine Tool Company,
Cincinnati, Ohio, a corporation of Delaware

Application May 12, 1943, Serial No. 110,195

Term of patent 14 years

To all whom it may concern:

Be it known that I, William F. Groene, a citizen of the United States and a resident of Cincinnati, county of Hamilton, and State of Ohio, have invented a new, original, and ornamental Design for a Lathe, of which the following is a specification, reference being had to the accompanying drawings, forming part thereof.

Figure I is a left-hand end front perspective of a lathe embodying my new design.

Figure II is a right-hand end front perspective view of the lathe shown in Figure I.

Figure III is a right-hand end rear perspective of the lathe incorporating my design.

Figure IV is a left-hand end rear perspective view of the lathe of Figure I.

Figure V is a perspective view of the left-hand end of the lathe.

Figure VI is a perspective view of the right-hand end of the lathe.

I claim:

The ornamental design for a lathe, substantially as shown.

WILLIAM F. GROENE.
